UNITED STATES PATENT OFFICE.

EDWARD E. HINRICHSEN, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

Application filed January 13, 1921. Serial No. 436,884.

To all whom it may concern:

Be it known that I, EDWARD E. HINRICHSEN, a citizen of the United States, residing at New York, in the county of New York, State of New York, have invented certain new and useful Improvements in Telephone Systems, of which the following is a full, clear, concise, and exact description.

This application relates to telephone systems and particularly to machine switching systems of the type in which relay mechanisms are employed for interconnecting the calling and called subscribers.

A feature of the invention is a new method for controlling the change-over from one brush to another by the direction switch employed for piloting the connections.

Another feature of the invention resides in the use of a direction switch by the attendant subscriber in place of the individual line selecting keys heretofore used in systems of this nature. By the use of such a direction switch the complete operation of this system is made more uniform and the number of devices under the control of the attendant operator is greatly reduced.

Another feature of the invention is a means whereby the attendant operator may set up a connection to a busy line and leave it in such a condition that the line will be automatically seized when the busy condition is removed.

Another feature of the invention is a new arrangement for signalling the central office when the battery supply for the system fails.

The drawings comprise a diagrammatic representation of a preferred means for carrying out the invention. There are four figures which, when placed together, Figure 2 below Figure 1, Figure 3 to the right of Figure 2 and Figure 4 above Figure 3 and to the right of Figure 1, form a complete circuit diagram.

Figure 1 contains a representation of two groups or subscribers' lines together with the necessary relays for connecting said lines to a central office trunk line; Figure 2 shows the means for connecting the said lines to a link circuit, and a link circuit to the said lines; Figure 3 shows a link circuit together with several auxiliary circuits such as the ringing circuit, the busy tone circuit and the buzzer circuit; and Figure 4 shows a central office trunk line.

In the drawings, a system of about eighty lines' capacity is represented. A call from one station to another is made by dialing the number of the called station. An originating call to the central office is made by dialing the central office code which connects the calling station to the central office so that the subscriber may give the desired number to the operator thereat. The disconnect signal is given to the central office when the calling subscriber hangs up. The calling subscriber can also flash the operator by manipulating his switchhook in the usual manner.

An incoming call is received by the attendant subscriber and may be extended to any desired station by the operation of her calling dial. The supervisory relay at the central office is operated as soon as the attendant answers the call and remains operated until the called station has answered and hung up again or until the attendant subscriber operates a disconnect key in case the call is not extended to a station. A disconnect signal is given to the central office automatically when the called subscriber hangs up at the end of the conversation but provision is made for the called subscriber to signal the attendant if desired.

Calls to the central office may be originated by the attendant and extended to any desired station.

The link circuits to be used in establishing local connections are not used on central office connections. Each trunk is provided with apparatus for connecting directly to any line and when a calling subscriber dials the central office code the link circuit to which he was originally connected functions to select an idle trunk and connects it to his line and then releases ready for use on another connection.

Provision is made for preventing any line from calling the central office directly. Incoming calls may, however, be completed to such lines.

The circuit arrangements are such that the connection links are used in rotation. A link having once been selected remains busy to incoming calls until all the other link circuits have been used even though it has been released in the mean time.

If the link circuit selected by an incoming call fails to pick up the calling line the call is transferred after a brief interval to the

next idle link circuit. Provision is made to reduce the possibility of more than one calling line being picked up by the same line finder in the case of simultaneous calls by the division of the lines into small groups and circuit arrangement which permits calls from only one group at a time to actuate a line finder.

10 The trunk selecting apparatus is so arranged that only one line at a time can originate a call to the central office thus avoiding double connections.

15 The detailed operation of the individual circuits shown on the drawing is as follows:

Line circuit.

When a subscriber such as 111 originates a call, a line relay such as 200 operates in series with his telephone set controlling the 20 operation of other relays which causes an idle link circuit to connect to the line. As soon as the connection has been made the sleeve conductor of the calling line is grounded in the link circuit making the line 25 busy to any link circuits or trunks which may select it and operates cut-off relay 201 which releases the line relay 200. When the line is released at the end of the connection the removal of the ground from the sleeve 30 conductor releases the cut-off relay and leaves the line free to be called.

Group circuit and emergency start circuit.

When the relay 200 operates it causes the 35 operation of group relay 202 through a circuit from ground, front contact and left hand armature of relay 200, winding of relay 202 to battery and ground. Relay 202 in attracting its armatures establishes a connection from ground, inner right hand armature and back contact of relay 203, outer right hand armature and front contact of relay 202, conductor 204, left hand armature and back contact of relay 300, conductor 301, armature and back contact of relay 205, left hand armature and back contact of relay 206, winding of relay 207 to battery and ground. Relay 207 becomes energized in this circuit and then locks up 40 in a circuit including conductor 301, the winding of relay 205, the right hand armature and front contact of relay 207, the winding of relay 207 to battery and ground. Circuits are thereupon established for relays 45 208, and 209. The circuit for relay 208 extends from grounded battery, the winding of relay 208, the next to the outermost left hand armature and front contact of relay 207, the front contact and inner right hand armature of relay 202, the back contact and inner right hand armature of relay 203 to ground. A circuit for relay 209 extends from grounded battery, the winding of relay 209, the innermost left hand armature and contact of relay 207, the front con-

tact and right hand armature of relay 200, the front contact and left hand armature of relay 202, the back contact and left hand armature of relay 203 to ground.

Through the action of relays 208 and 209, 70 the calling line is extended to the link circuit of Figure 3, whereupon the calling supervisory relay 302 is operated by the closed loop of the calling subscriber's line. Relay 302 closes a circuit from ground, the 75 winding of relay 303 the left hand armature and front contact of relay 302, right hand armature and back contact of relay 304, winding of relay 305 to battery and ground. Relay 305 attracts its armatures and places 80 a ground on conductor 306 to which relays 208 and 209 lock. The ground on conductor 306 is also extended through the contacts of relays 209 and 208 to the sleeve conductor of the calling line to operate the cut-off 85 relay 201.

The ground placed on conductor 204 by the operation of the group relay 202 causes the energization of relay 307 through the back contact of relay 308. Relay 307 connects conductor 204 to the winding of relay 308 so that relay 308 then operates. Relay 307 and 308 being slow to release will remain energized for a short interval whereupon relay 307 will become deenergized. Upon the 95 release of relay 307 a circuit is established from ground on conductor 204 through the armature and front contact of relay 308, the back contact and right hand armature of relay 307, the outermost right hand armature and back contact of relay 300, the winding of relay 309, the back contact and innermost right hand armature of relay 300 to battery and ground, whereupon relay 309 becomes energized. When this ground is 100 removed by the subsequent release of relay 308, relay 309 remains locked up through the winding of relay 300 which thereupon 105 operates. This circuit is as follows: ground on conductor 204, left hand winding 110 of relay 300, inner left hand armature and front contact of relay 309, winding of relay 309 back contact and inner right hand armature of relay 300 to battery and ground. As soon as relay 300 operates the circuit is 115 as follows: ground on conductor 204, the left hand winding of relay 300, inner left hand armature and front contact of relay 309, winding of relay 309, right hand winding 120 of relay 300 to battery and ground.

The cycle of operations of relays 307 and 308 is repeated and on the next release of relay 307, relay 309 is short-circuited and released, relay 300 being held up until relay 308 releases. This momentarily opens the 125 start lead 301 and closes an emergency lead which advances the selection to the next link circuit. When this condition is established there will be a circuit from ground on conductor 204, the left hand armature and front 130

contact of relay 300, back contact and outer left hand armature of relay 309, emergency lead 310, left hand armature and back contact of relay 210, right hand winding of relay 206 to battery and ground. Relay 206 becomes energized and extends conductor 301 to conductor 211 leading to a left hand armature of a relay 212 individual to the next link circuit and performing the same 10 functions as relay 206. Thus when a call is initiated it must be picked up by the first idle link circuit very quickly or the emergency circuit will operate to make effective the next idle link circuit.

15

Link circuit.

The link circuit comprises three parts; a set of finder relays, a set of connecting relays and the apparatus for controlling the operations of the finder and connecting relays 20 20 supplying transmitter current and testing and ringing the called lines.

When a station originates a call, the operation of a group relay such as 202 operates 25 a relay such as 207 through the back contact of the allotter relay such as 206. The operation of relay 207 connects the relays such as 209 to the contacts of the line relays and connects the relays such as 208 to the contacts 30 of the group relays such as 202. This causes the operation of the relay 208 corresponding to the group of ten lines in which the calling line is located and relay 209 corresponding to its position in the group. This connects 35 the talking circuit to the calling supervisory relay 302 individual to the link circuit, which operates, operating in turn the holding relay 305. Relay 305 when operated closes a locking circuit for relays 208 and 40 209 and supplies ground for operating the cut-off relay 201 for the calling line and operating the allotter relay 206.

Assuming that the link circuit, whose operation is being described, is any other than 45 the last, relay 206 locks up through its right hand winding and contact, the winding of relay 210 and the back contact of relay 213 of the last link circuit, this circuit being as follows: ground, armature and back contact 50 of relay 213, front contact and right hand armature of relay 206, winding of relay 210, right hand winding of relay 206, to battery and ground.

The operating circuit of relay 207 is opened 55 by the operation of relay 206, but relay 207 is locked up through relay 205 which operates and prevents the operation of relay 206 from operating the relay corresponding to relay 207 of the next link circuit. Relay 205 60 which is common to all the links releases upon the release of relay 202 of the group circuit. Relays 206 and 210 remain locked up independently of the remaining apparatus of the link circuit until released by the 65 operation of relay 213 of the last link cir-

cuit. When the last link circuit is selected and its relay 214 operates, it locks up through its right hand winding and contact and winding of relay 214 and contacts of the corresponding relays of all other link circuits in series. Relay 213, of the last link operating, opens the locking circuit for relays corresponding to 206 and 210 in all the other link circuits, releasing relays corresponding to 206 of such link circuits as are 70 not in actual use. The release of relays corresponding to relay 210 in any other of the link circuits releases relay 213 of the last link circuit and reestablishes the locking circuits for the relays corresponding to 206. 80

In case of trouble in a link circuit which prevents relays corresponding to relay 206 from operating in the normal manner within a predetermined time, the action of the emergency start circuit grounds the emergency start lead 310 which operates relay 206 through its right hand winding and at the same time opens the regular start lead 301 and releases relays 207 and 205. As soon as the action of the emergency circuit removes the ground from the emergency start lead 210 operates and relay 212 of the next link is operated.

When the holding relay 305 operates it closes the operating circuit for relay 312. 95 Relay 312, however, does not operate since it is short-circuited by a contact of the supervisory relay 202. When the subscriber operates his dial, relay 302 releases in response to each interruption of the line circuit by the dial springs, permitting relay 312 to operate. The operating circuit for relay 312 is then as follows: grounded battery, resistance 314, winding of relay 312, back contact and inner right hand armature 100 of relay 313, conductor 306, front contact and right hand armature of relay 305 to ground. Relay 312, in operating, operates magnet 315 which steps the direction switch ahead. Magnet 315 controls an extra armature which closes a contact to operate magnet 316. The armature of magnet 315 which controls its contacts is slow in releasing, so that it does not fall back on a momentary release of relay 312, although the other armature follows the impulses received from relay 312 and steps the switch ahead. Magnet 316, when it operates, permits the holding pawl of the switch to engage with its ratchet so that the switch does not release so 110 long as magnet 316 is energized. When the dial comes to rest relay 302 remains operated and relay 312 is released long enough to permit both armatures of magnet 315 to release. Magnet 316 is slow to release so that 120 it remains operated momentarily after the release of relay 315, grounding the group brush 317 and operating the connecting relay associated with the group of ten lines in which the called line is located. We will as- 130

sume that the calling line 111 is establishing a call to the line 191. In this case the number of the called line is 91 so that the first set of impulses consists of nine interruptions of the calling line circuit and results in the movement of brush 317 to its ninth contact where it will ground conductor 318 leading to relay 215. In this manner relay 215 will become operated. The original operating circuit of relay 215 is opened on the release of magnet 316 but relay 215 remains operated in series with relay 319 which itself becomes energized. This circuit is as follows: ground on conductor 306, winding of relay 319, conductor 320, right hand armature and front contact of relay 215, winding of relay 215 to battery and ground. The release of magnet 316 removes the pawl from engagement with its ratchet and permits the direction switch to return to normal.

Relays 302 and 312 and magnets 315 and 316 function in the same manner responsive to the second operation of the dial but as relay 319 is now operated, magnet 316 in operating, energizes relay 321 in a circuit extending from ground, right hand armature and front contact of magnet 316, innermost right hand armature and front contact of relay 319, winding of relay 321 to battery and ground. When magnet 316 releases after the dial comes to rest the units brush 322 is grounded, operating the units relay corresponding to the position of the called line in its group. In accordance with our assumption this unit series of impulses consists of a single interruption of the calling line circuit and brush 322 comes to rest on its first contact and grounds conductor 323 operating thereby units relay 216.

Assuming the called line 191 to be busy and the cut-off relay 247 to be operated by ground on the sleeve 248 of the called line, then upon the operation of relays 215 and 216 a circuit will be established from ground on the sleeve 248 of the called line through the corresponding contacts of relays 215 and 216 to the sleeve conductor 324 of the link circuit through the left hand armature and front contact of relay 321, the normal contacts of the inner left hand armature of relay 313, the winding of relay 313 to battery and ground. Relay 313 operates and locks up to ground on conductor 306 in turn locking up relay 321 in a circuit from battery, winding of relay 321, front contact and armature of relay 321, front contact and innermost right hand armature of relay 313 to ground on conductor 306. Relay 313 also opens the circuit of relay 312 to prevent the direction switch from responding to any further movement of the dial and connects busy tone through the condenser 326 to the calling subscriber. The path of the busy tone is as follows: from conductor 327, leading from a source of busy tone through the

front contact and outermost left hand armature of relay 313, conductor 328, back contact and outermost right hand armature of relay 325, condenser 326, right hand winding of relay 329 to battery, whence by inductance in the windings of relay 329 busy tone is transmitted over the talking leads to the calling subscriber's telephone.

The busy tone is supplied in the following manner: Relay 303 is energized in series with relay 305 in a circuit heretofore described. The operation of relay 303 closes a circuit from ground, the armature and front contact of relay 303, the back contact and armature of magnet 330, winding of magnet 330 to battery and ground. Magnet 330 attracts its armature and automatically interrupts its circuit. This causes a rapid automatic vibration of the armature of magnet 330 which so effects the potential on conductor 327 that a tone is set up thereon.

Assuming the called line to be idle, relay 313 does not operate because battery connected to its winding is opposed by battery connected to the winding of cut-off relay 247. Upon the release of magnet 316, relay 321 becomes deenergized. This connects the sleeve 324 through a back contact of relay 325 to a winding of supervisory relay 329 which becomes operated and causes the operation of relay 313. A circuit for the energization of relay 329 is as follows: from grounded battery, the winding of cut-off relay 247, sleeve conductor 248, through the corresponding contacts of relays 215 and 216, conductor 324, left hand armature and back contact of relay 321, normal contact of the innermost right hand armature of relay 325, left hand winding of relay 329 to ground. Relay 329 in attracting its armature extends the ground on conductor 306 through its contact and armature to the normal contacts of the innermost left hand armature of relay 313, the winding of relay 313 to battery and ground. Relay 313 becomes energized and locks up in the circuit previously traced.

Since relay 321 is deenergized at this time a circuit will be established for relay 325, said circuit extending from grounded battery, winding of relay 325, back contact and right hand armature of relay 321, front contact and innermost right hand armature of relay 313 to ground on conductor 306. Relay 325 transfers the sleeve conductor 324 from the left hand winding of relay 329 to a ground connection on conductor 306. Relay 325 also connects the tip and ring of the called line to the armatures of ringing relay 331.

Interrupted ringing current is now supplied to the called line from the source of such ringing current shown in the right hand portion of Figure 3, conductor 332 and left hand winding of ringing relay 331, back contact and outer left hand ar-

ture of relay 331, front contact and innermost left hand armature of relay 325 through contacts of relays 216 and 215 over the loop of the called substation 191, back 5 through the contacts of relays 215 and 216, the outermost left hand armature and front contact of relay 325, the innermost left hand armature and back contact of relay 331, conductor 333 to ground. The current 10 in this circuit is insufficient to energize the relay 331 until it is increased by the removal of the receiver at the called substation. Thereupon relay 331 attracts its armatures and locks itself in a circuit including its 15 right hand winding, its front contact and innermost right hand armature to ground on conductor 306. Through its left hand armatures it extends the called line to control of the called supervisory relay 329. 20 Talking current is supplied to the called line through the windings of relay 329 and to the calling line through the windings of relay 302. The connection is now in a 25 stable condition and conversation may now be carried on.

At the end of the conversation the release of the apparatus is effected by the calling station replacing its receiver and causing the deenergization of relay 302. 30 Relay 302 in retracting its armatures releases its control over the holding relay 305 and when after an interval this relay becomes released, all of the relays under its control return to normal and the connection is restored.

In case the trunk code is dialed, relay 304 becomes operated in place of one of the relays corresponding to relay 215 and relay 304 locks up in a circuit including battery, its winding, its front contact and innermost left hand armature and the front contact and left hand armature of the holding relay 305 to ground. The trunk relay 304 opens the operating circuit of 40 the holding relay 305 and connects ground from the front contact of relay 302 to a relay in the first idle trunk circuit. This circuit extends from ground, winding of relay 303, left hand armature and front contact of relay 302, right hand armature and front contact of relay 304, conductor 334, innermost left hand armature and back contact of relay 400, winding of relay 100 to battery and ground and in parallel therewith through the back contact and outermost right hand armature of relay 400 to the winding of holding relay 401 to battery and ground.

Upon the operation of relay 304, a circuit is established for the operation of relay 335 as follows: ground, fourth armature of the set of left hand armatures of relay 208 individual to line 111, outermost left hand armature and front contact of relay 209, conductor 217, outermost left

hand armature and front contact of relay 304, left hand winding of relay 335, back contact and armature of relay 336 to battery and ground. Relay 335 becomes energized and extends the ground on conductor 217 through its outermost left hand armature, conductor 337, outermost right hand armature and front contact of relay 208, conductor 218, armature 101 of relay 100 and front contact co-operating with said 70 armature, winding of relay 102 to battery and ground causing the energization of said relay 102. A circuit is also established from ground on conductor 217 through the innermost left hand armature and front contact of relay 335, conductor 338, outermost right hand armature and front contact of relay 209, conductor 219, innermost left hand armature and front contact of relay 100, winding of relay 103 to battery and 80 ground causing the energization of said relay 103. Relay 335 also completes a circuit from ground on conductor 311, right hand armature and front contact of relay 335, right hand winding of relay 335, winding of relay 336 to battery and ground; whereby relay 336 is energized to open the original energizing circuit of relay 335. Relay 335 is individual to the link circuit but relay 336 is common to all link circuits 90 so that when relay 336 operates it prevents the operation of any other relay corresponding to relay 335 until the one here shown becomes deenergized.

The operation of relays 102 and 103 extends the calling line to the trunk shown in Figure 4. Relay 102 is then locked up in a circuit from ground, the right hand armature and front contact of relay 401, contacts 402 of key 403, back contact and outermost right hand armature of relay 404, conductor 405, front contact and armature of relay 102, winding of relay 102 to battery and ground. Relay 103 is also locked up in a circuit including ground, right hand armature and front contact of relay 401, contacts 402 of key 403, conductor 406, front contact and armature of relay 103, winding of relay 103 to battery and ground. Ground was also extended from conductor 100 406, through the right hand armature and front contact of relay 100, conductor 104, right hand winding of relay 407 to battery and ground. Relay 407 locks up 105 through its front contact and innermost right hand armature to ground on conductor 406. 110

Relay 401 also places ground on conductor 408 for a purpose which will appear hereafter. The busy lamp 409 is illuminated in 125 response to the energization of relay 401. Relay 400 is short-circuited through its own back contacts and by the ground on conductor 334 and will not become energized until relay 302 releases. It will be remembered 130

- that the energization of relay 304 which sets in motion the train of operations just described opens the circuit for relay 305. In a short interval relay 305 becomes deenergized 5 and by removing ground from conductors 306 and 311 allows all of the relays of the link circuit to release with the exception of relays 206 and 210. Upon the release of relay 302, relay 400 becomes energized.
- 10 In case the calling line is not arranged for connections to the central office it does not supply current to the contacts of relays 304 and 335 so that relay 335 does not operate and the trunk selected by the link is not connected to the line. Such restricted service 15 is accomplished through the simple expedient of omitting the ground connection to the fourth conductor of the calling line. If, for instance, line 110 were arranged for restricted service there would be no ground connection to the innermost left hand armature of relay 208. If a subscriber on such a line attempts to call the central office, the link circuit releases without the line becoming 20 connected to a trunk and the calling line is advanced and picked up by the same link circuit or some other. Under this condition busy tone is supplied to the calling subscriber through the back contact of relay 25 319. This tone also serves as a dial tone to indicate to the subscriber, when he originates a call, that his line has been picked up by a link circuit, it is cut-off by the operation of relay 319 after the first movement of the 30 dial.

Trunk circuit—originating calls.

When any line dials a central office code the link circuit functions in such a way as 40 to place ground through the back contacts of relay 400 on the windings of relays 401 and 100, operating them and supplies ground through the contacts of relay 100 to the relay 102 associated with a group of ten lines 45 in which the calling line is located and the relay 103 corresponding to the different positions in the group. Relay 401 lights lamp 409, supplies current for locking up relays 102 and 103 and operates relay 407 through 50 a contact of relay 100. Relay 410 is normal so that the sleeve of the calling line is connected through resistance 411 and relay 412 to the ground. This last circuit may be traced from the cut-off relay 201, sleeve of 55 the calling line through the corresponding contacts of relays 102 and 103, sleeve conductor 413, left hand armature and back contact of relay 410, normal contacts of the outermost right hand armature of relay 414, 60 resistance 411, winding of relay 412, contacts 415 of key 403, front contact and right hand armature of relay 401 to ground. As soon as the link circuit releases and removes ground from the sleeve of the calling line, 65 relay 412 operates, operating relay 416 in a

circuit extending from grounded battery, winding of relay 416, contacts 417 of key 403, innermost right hand armature and front contact of relay 412, winding of relay 412, contacts 415, of key 403, front contact 70 and right hand armature of relay 401 to ground. Relay 416 becomes energized and completes a circuit for relay 414 as follows: grounded battery, winding of relay 414, front contact and left hand armature of 75 relay 412, back contact and innermost right hand armature of relay 410, outermost left hand armature and front contact of relay 416, contacts 418 of key 419 to ground. Relay 414 is energized in this circuit. A circuit is thereupon set up from ground, outermost right hand armature and front contact 80 of relay 414 back contact and left hand armature of relay 410, sleeve conductor 413, to the cut-off relay of the calling line. Through its left hand armatures, relay 414 connects the tip and ring of the calling line to the trunk circuit whereby the calling line is put in the control of relay 420. The operation of relay 401 closes an operating circuit for relay 400 but this relay is short-circuited through its own back contact from ground from the link circuit, so that it does not operate until the removal of this ground. 85 As soon as this ground is removed and relay 400 operates, it transfers the starter lead from the link circuit to the next trunk circuit and places relay 401 under control of relay 420. This circuit may be traced as follows: from grounded battery, winding of 90 relay 401, outermost right hand armature and front contact of relay 400, front contact and left hand armature of relay 420, conductor 421, winding of relay 303 to ground. 95 Relay 420 in operating grounds the tip side 105 of the line to the central office operating the line circuit thereat. This circuit may be traced as follows: from ground, front contact and right hand armature of relay 420, innermost right hand armature and back 110 contact of relay 422, tip side of the trunk, contacts 423 of key 424, back contact and armature of cut-off relay 425, winding of relay 426, to battery and ground. Relay 426 attracts its armatures and establishes a 115 circuit to light line lamp 427. Relay 420 also operates relay 428 through a circuit extending from grounded battery, winding of relay 428, contacts 429 of key 430, contacts 431 of key 403, normal contacts 120 of the innermost left hand armature of relay 428, front contact and left hand armature of relay 420 winding of relay 303 to ground. Relay 428 attracts its armature and locks up in a circuit from ground, left hand armature and front contact of relay 401, conductor 408, innermost left hand armature and front contact of relay 428, contacts 431 125 of key 403, contacts 429 of key 430, winding of relay 428 to battery and ground. Relay 130

428 in operating opens the circuit of relay 433.

As soon as the call has been answered by an operator, relay 432 operates in a circuit including ground, the tip conductor of the trunk at the central office, contacts 423 of key 424, contacts 434 of key 430, right and left hand windings of relay 432 in series, contacts 435 of key 424, ring conductor of the trunk at the central office to grounded battery. Relay 432 in operating causes the operation of relay 436. The relay 436 connects relay 437 in a circuit which may be traced from grounded battery, winding of relay 437, contacts 438 of key 430, front contact and outermost left hand armature of relay 428, left hand armature and front contact of relay 436 to ground. Relay 437 in operating extends the calling line to the central office. Relay 420 is cut off and de-energized but relay 401 is held operated by the outermost left hand armature and front contact of relay 437, whereupon relay 439 operates in series with the calling line and in turn causes the operation of relay 440. Relay 440 opens the circuit of relay 432 and places a non-inductive shunt 441 across the winding of the supervisory relay 439. Relay 436 is maintained operated by relay 439. The connection is now in a stable condition and the subscriber may converse with the operator at the central office.

When the subscriber hangs up, relays 439 and 440 release permitting relay 432 to operate which prevents the release of relay 436. The high resistance of relay 432 releases the supervisory relay at the central office. As soon as the disconnection takes place at the central office, relay 432 releases, releasing relay 436. This releases relay 437 which in turn releases relay 401 and then in turn releases the remaining operated relays of the circuit.

If the operator should disconnect before the subscriber hangs up, relays 439 and 440 release, but relay 432 does not operate and relay 436 releases. This releases relay 437 and permits relay 420 to operate. This holds up relay 401 and grounds the tip side of the line operating the line relay again at the central office and relighting the line lamp. When the operator restores the connection, relays 432, 436, and 437 operate and relay 420 releases.

55 Incoming calls.

When an operator plugs into a trunk with a cord circuit, relay 432 operates, operating in turn relay 436. This lights the busy lamp 409 and operates relay 400, preventing the trunk from being selected by any subscriber who is calling central.

As soon as ringing current is supplied to the line at the central office, relay 433 operates and locks up, lighting the line lamp 442.

The circuit for lamp 442 may be traced as follows: from a source of ringing current, ring side of the line at the central office, contacts 435 of key 424, condenser 443, right hand winding of relay 433 right hand armature and back contact of relay 428, contacts 434 of key 430, contacts 423 of key 424, tip side of the line to ground at the central office. Relay 433 when operating closes a circuit from battery, winding of relay 339, line lamp 442, right hand armature and front contact of relay 433, back contact and innermost left hand armature of relay 422, normal contacts of the innermost left hand armature of relay 444, conductor 445, right hand armature and front contact of relay 436 to ground. Relay 433 locks up in a circuit including battery and ground, its left hand winding, its left hand armature and front contact to ground over the circuit just traced. The attendant subscriber at station 490 answers by means of the listening key 446, operating thereby relay 422 which releases relay 433 and extinguishes line lamp 442. The circuit for relay 422 may be traced from grounded battery, winding of relay 422, contacts 447 of key 446 to ground. Guard lamp 448 lights as it is in multiple with the winding of relay 422. Relay 439 operates, operating relay 440 which bridges the non-inductive shunt 441 across the winding of relay 439. Retardation coil 449 was bridged across the line in series with the low resistance winding of relay 432 by the operation of relay 422 and a short-circuit is removed from its middle high resistance winding by the operation of relay 440. Relay 432 may release but relay 436 is held operated by contacts of relay 439.

To extend the call to a station, the attendant subscriber operates the station key which comprises the left hand contacts of key 430. This opens the circuit of relay 428 and operates relay 105. The circuit for relay 105 may be traced from grounded battery, winding of relay 105, conductor 106, normal contacts of the inner right hand armature of relay 416, contacts 450 of key 430, contacts 451 of key 446 to ground. Relay 105 connects the trunk to the common selecting apparatus and operates relay 404 in a circuit including grounded battery, winding of relay 404, conductor 452 innermost right hand armature and front contact of relay 105 to ground. Relay 404 when operating transfers the attendant subscriber's telephone set to the other side of the contacts of relay 437 thereby operating relay 420. Relays 439 and 440 release, but relay 422 remains operated. The release of relay 440 short-circuits the high resistance winding of the retardation coil 449 and relay 432 operates and prevents the release of relay 436. Relay 401 operates and closes an operating circuit for relay 107 which however is

short-circuited at this time so that it does not operate. The circuit for causing this may be traced from the top side of relay 107 through contacts 108 of relay 105, conductor 109 front contact and innermost right hand armature of relay 422, right hand armature and front contact of relay 420 to ground and from the lower terminal of relay 107 to contacts 112 of relay 105, conductor 408, to ground on the left hand armature of relay 401.

The attendant subscriber now operates her dial to select the desired number and relay 420 releases at each interruption of the circuit by the dial springs, permitting relay 107 to operate. Relay 107 in operating, operates stepping magnet 113 of the switch which steps the wiper ahead. Magnet 113 carries an extra armature which controls a contact which operates magnet 114. Magnet 114 in operating allows the holding pawl of the switch to engage with its ratchet and closes a circuit through its innermost right hand armature and front contact and the back contact of relay 115 to group brush 116. The armature of magnet 113 which operates the contacts is sluggish so that it does not release when relay 107 is momentarily released in response to the dial impulses although the other armature follows the impulses received from relay 107 and advances the switch to the operating position. When the dial comes to rest, relay 107 is released long enough to permit both armatures of magnet 113 to release. Magnet 114 is sluggish so that it remains operated momentarily so that the group brush 116 is grounded, operating the connecting relay associated with the group of ten lines containing the called line.

We will assume that a call is being set up to the subscriber at station 110; therefore the set of impulses for moving the group brush 116 consists of a single interruption of the attendant subscriber's line circuit and group brush 116 comes to rest on its first contact. Upon the release of magnet 113, conductor 117 is grounded, causing the operation of relay 102. The circuit for the energization of relay 102 may be traced from ground, the armature and back contact of magnet 113, the innermost right hand armature and front contact of magnet 114, the left hand armature and back contact of relay 115 group brush 116, conductor 117, contacts 118 of relay 105, winding of relay 102 to battery and ground. Relay 102 locks up to ground on conductor 405, which ground is supplied from the left hand armature and front contact of relay 401, conductor 408, contacts 112 of relay 105, winding of relay 115, contacts 119 of relay 105, to conductor 405. Relay 115 is operated in this circuit. In a short interval magnet 114 retracts its armatures

and permits the switch to return to normal. Relays 420, 107 and magnets 113 and 114 function in the same manner in response to the second operation of the dial but as the relay 115 is now operated the operation of magnet 114 operates relay 410 in a circuit including grounded battery relay 410, conductor 453, outermost right hand armature and front contact of relay 105 front contact and outermost right hand armature of magnet 114, front contact and right hand armature of relay 115 to ground. When magnet 113 releases it grounds the units brush 120, operating the units relay corresponding to the position in its group of the called line. In accordance with our assumption, this last series of impulses consists of ten interruptions of the attendant subscriber's line. This causes the units brush 120 to come to rest on its tenth contact and ground conductor 121 whereupon relay 122 is operated. The circuit for the operation of relay 122 may be traced as follows: grounded battery, relay 122, contacts 123 of relay 105, conductor 121, units brush 120, front contact and left hand armature of relay 115, front contact and inner right hand armature of magnet 114, back contact of magnet 113 to ground. Relay 122 is energized in this circuit and locks up to ground on conductor 406. The co-operation of relays 102 and 122 connects the desired line to the trunk circuit. As relay 410 is operated, the sleeve of the called line is connected through the winding of relay 416 to battery. This circuit may be traced as follows: sleeve of the called line through the corresponding contacts of relays 102 and 122, sleeve conductor 413, left hand armature and front contact of relay 410, normal contacts of the inner left hand armature of relay 416, contacts 417 of key 403, winding of relay 416 to battery and ground.

If the line is busy the sleeve is grounded so that relay 416 operates and locks up, in turn locking up relay 410. The operation of relay 416 also releases relay 105, leaving relay 107 directly under control of the station key comprising the left hand contacts of key 430. The release of relay 105 opens the holding circuit for relay 102, but the ground connection for locking up relay 102 is now furnished by the operation of relay 416.

In case the line is not busy, relay 416 does not operate and relay 410 releases upon the release of magnet 114 connecting the sleeve through the resistance 411 and relay 412 to ground. Relay 412 operates in series with the cut-off relay of the line and locks up through relay 416 which operates, cutting off and releasing relay 105. As relay 410 is now normal and relay 412 is operated, the operation of relay 416 operates relay 414 which cuts the sleeve of

the line off of relay 412 and grounds it direct and cuts the tip and ring through to the ringing relay 407. Relay 414 also connects condenser 454 across the contacts of relay 407.

Interrupted ringing current is now supplied to the called line through the back contact and left hand winding of relay 407. Direct current is supplied to the line through the winding of relay 407 during the silent intervals and is superimposed on the alternating current during the ringing intervals. The operating circuit of the ringing interrupters is closed by the operation of relay 400.

The attendant may now restore her keys. Relay 407 does not operate on the current which passes through the subscriber's bell but as soon as the subscriber answers he closes a path through his telephone set for direct current which operates relay 407. Relay 407 locks up through its right hand winding and connects the subscriber through to relay 420 and opens the operating circuit of the ringing interrupters. Relay 420 operates, operating relay 401 and as the station key has been restored to normal, relay 428 also operates. As relay 436 is operated, this causes the operation of relay 437 cutting the line through to the central office and operating relays 439 and 440. As relay 422 is operated, the operation of relay 440 causes the operation of relay 444, the circuit for which may be traced from grounded battery, left hand winding of relay 444, outer left hand armature and front contact of relay 422, outer right hand armature and front contact of relay 428, front contact and inner left hand armature of relay 440 to ground. Relay 444 locks up to ground on conductor 406 and places the locking circuit of relay 422 under the control of relay 440 and also operates relay 455 under the control of relay 440 which extinguishes the guard lamp 448. The operation of relay 440 also bridges the non-inductive shunt 441 across the winding of the supervisory relay 439 and removes the short-circuit from the high resistance winding of the retardation coil 449. The connection is now in a stable condition and conversation may proceed.

When the subscriber hangs up relays 439 and 440 release releasing in turn relays 422 and 455. Relay 432 operates preventing the release of relay 436. The bridge through the retardation coil 449 is removed from the line by the release of relays 422 and 455 and the high resistance of relay 432 permits the release of the supervisory relay at the central office. When the disconnection takes place at the central office, relay 432 releases, releasing relay 436. This releases relay 437 and relay 401 which in

turn release all other operated relays and 65 restores the circuit to normal.

The subscriber may recall the attendant by depressing the switch hook momentarily or operating his dial, thus releasing relay 440 momentarily, which releases relay 422. 70 As relay 444 remains operated line lamp 442 is lighted but relay 455 remains operated preventing the guard lamp 448 from lighting. Relay 455 is slow in releasing so as to prevent disturbance of the apparatus at 75 the central office by a momentary interruption of the circuit through the subscriber's telephone. The attendant subscriber answers by operating her listening key 446 which bridges her telephone set across the 80 line and causes relay 422 to operate and lock up. In case she has occasion to transfer the call to another line she operates a release key 403 which releases relays 428, 444, 416, 412, 414, 407, 102 and 122. Relay 85 455 is released by the release of relay 444 and guard lamp 448 lights. The attendant may now operate her station key comprising the right hand contacts of key 430 and select another station in the manner already 90 described.

In case the line which the attendant selects is busy she may, if the importance of the incoming call appears to justify it, break in upon the conversation by operating key 95 419. This releases relay 410 and cuts off the busy tone and operates the contacts of relays 414 and 407 so that the attendant's telephone set is connected to the called line. The release of key 419 does not operate 100 relay 410 again so that the sleeve of the line is connected through resistance 411 and relay 412. Relay 412, however, does not operate since the sleeve of the line is grounded. When the called line becomes free, the removal of the ground from its sleeve permits 105 relay 412 to operate and lock up through relay 416 and operate relay 414. The line is now connected through to relay 407 so that the subscriber's bell rings and the remainder of the operation is the same as if the line had not been busy. In case the attendant does not wish to wait for the line to become idle, she may operate the release key 403 after releasing key 419 and then 110 115 select another line.

In case the attendant subscriber receives an incoming call which is not extended to a station she may give the disconnect signal to the central office by restoring her listening key and operating the disconnect key 424. This releases relay 422 opening the bridge through the retardation coil 449. The disconnect key 424 may be used as a 120 125 flashing key for signaling the operator by operating it when the listening key is operated. This opens the line to the central office releasing the supervisory relay there-

at but relay 439 remains operated in series with the telephone set and resistances 456 and 457, preventing the release of relay 436.

5 Calls originated by attendant subscriber.

The attendant subscriber may originate a call to the central office by operating the listening key. This grounds the tip of the trunk through a back contact of relay 436 10 and a back contact of relay 404 operating the line relay at the central office. At the same time the depression of the listening key 446 operates relay 422 which grounds the sleeve of the trunk, lighting the busy lamp 15 409 and operating relay 400. When the operator at the central office answers relay 439 operates, operating in turn relays 440 and 436.

After the attendant has originated a call 20 to the central office, she may extend it to any station just as if it were an incoming call.

The attendant may call any station over a trunk by operating the station key and 25 the listening key and selecting the station in the same manner as described for the incoming call. The operation of relay 404 cuts off the calling-in ground so that the line relay at the central office is not operated. 30 The call may be extended to the central office by restoring the station key and leaving the listening key operated until the central office has answered.

In case of a failure in the battery supply 35 within this system the attendant may call the central office by operating the central office key comprising the right hand contacts of key 430, the listening key 446 and the emergency key 458. The central office 40 key in addition to cutting off the bridges across the circuit, places a non-inductive shunt across the winding of relay 439. Under this condition, relay 459 operates as soon as the operator at the central office answers, and removes the calling-in ground 45 from the line.

Ringing circuit.

Whenever any link circuit or trunk circuit 50 is in the ringing condition relay 340 is operated. This closes a circuit for operating relay 341 which operates and locks up, and operates relay 342. Relay 342 opens the operating circuit of relay 341 and locks 55 up and short-circuits and releases relay 341. Relay 341 in releasing opens the operating circuit of relay 342 and short-circuits and releases it. The release of relay 342 allows relay 341 to operate again and this cycle of 60 operations continues as long as relay 340 remains operated. Ground is connected first to one and then to the other of the primary windings of the ringing transformer 343 by the contacts of relay 342 so that an alternating current is induced in the secondary

winding of the transformer 343 as long as the common point of the primaries is connected to battery through the front contact of relay 344 and the back contact of relay 345. Relay 340 also closes an operating 70 circuit for relay 346 which operates and locks up and operates in turn relay 347. Relay 347 in operating opens the operating circuit of relay 346 and short-circuits and releases it. Relay 346 in releasing releases 75 relay 347, this permits relay 346 to operate again and the cycle of operations is repeated as long as relay 340 remains operated. As soon as relay 340 operates it operates relay 344 through the back contacts of relays 347 and 345 connecting battery to the primary windings of the ringing transformer 343. When relay 347 operates relay 344 is locked up through the right hand winding 80 of relay 345. Relay 345 operates removing the short-circuit from its left hand winding and cuts off battery from the ringing transformer 343. When relay 347 releases it short-circuits and releases relay 344 but relay 345 remains locked up through its left 85 hand winding. On the next operation of relay 347, relay 345 releases and when relay 347 releases again relay 344 operates and this cycle is repeated as long as relay 340 remains operated. Battery is supplied to the primary of the ringing transformer 343 whenever relay 344 is operated and relay 345 is normal. The period of operation of 90 relays 346 and 347 is such as to cause a series of short rings in any bell which may be connected to the secondary of the ringing transformer. 95

Tone circuit.

Whenever relay 302 of a link circuit or 105 relay 420 of a trunk circuit is operated relay 303 operates and closes a circuit through the back contact and winding of relay 330. Relay 330 operates as a buzzer and supplies busy tone and dial tone through the link 110 and trunk circuits.

Buzzer circuit.

Battery is supplied to the line lamps of the trunks through the relay 339 which operates whenever a line lamp is lighted and sounds the buzzer. The key 338 is furnished by means of which the buzzer may be silenced even though the line lamp is burning. When the relay 339 is operated and key 338 is normal a circuit is established from ground, the armature and front contact of relay 339, the left hand winding of relay 349, the back contact and armature of relay 350, the right hand winding of 120 relay 349 to grounded battery. Relay 350 acts as a buzzer and creates an audible tone to attract the attention of the attendant subscriber. 125

What is claimed is:

1. In a telephone system, telephone lines, relays for establishing connections between said lines, a plurality of said relays being employed in establishing a connection, directively operable means for energizing a plurality of said relays normally effective to energize one of said relays, and means responsive to the energization of said one of said relays for controlling said energizing means. 70
2. In a telephone system, telephone lines, groups of relays for establishing connections to said lines, a relay of each group being employed in establishing a connection, directively operable means for selectively energizing said relays, a relay associated with said means, means responsive to the selective energization of a connecting relay of one group for energizing said last relay, and means controlled by said last relay for changing the control of said energizing means from one group of said connecting relays to another group of said connecting relays. 80
3. In a telephone system, telephone lines, groups of relays for establishing connections to said lines, a direction switch for piloting said connections, and a relay associated with said direction switch responsive to the energization of a connecting relay in one of said groups for controlling said direction switch to cause energization of a connecting relay in another of said groups. 90
4. In a telephone system, telephone lines, switching devices having permanently paired primary and secondary contacts for establishing connections to said lines, means for operating said devices to establish connections to busy lines, and means responsive to the removal of the busy condition to automatically render such connections effective. 100
5. In a telephone system, a plurality of telephone lines, an operator's trunk, a central office trunk, switching devices having permanently paired primary and secondary contacts for interconnecting said lines and trunks, means for operating said devices to establish connections to busy lines, and means responsive to the removal of the busy condition to automatically render such connections effective. 110
6. In a telephone system, telephone lines, an operator's trunk, switching devices having permanently paired primary and secondary contacts for interconnecting said lines and said trunk, means under control of said operator's trunk for establishing a connection to a busy line, and means responsive to the removal of the busy condition to automatically render such connection effective. 120
7. In a telephone system, telephone lines, an operator's trunk, switching devices having permanently paired primary and secondary contacts for interconnecting said lines and said trunk, means under control of said operator's trunk for controlling said devices for establishing a connection to a busy line, and means responsive to the removal of the busy condition to automatically render such connection effective. 125
8. In a telephone system, telephone lines, an operator's trunk, switching devices having permanently paired primary and secondary contacts for interconnecting said lines and said trunk, a direction switch for controlling said devices, means for operating said direction switch to cause one of said devices to establish a connection to a busy line, and means responsive to the removal of the busy condition for rendering said connection effective. 130
9. In a telephone system, telephone lines, an operator's trunk, a sending dial associated with each of said lines and with said trunk, switching devices having permanently paired primary and secondary contacts for establishing interconnections between said lines and said trunk, a direction switch separate from said interconnections for controlling said devices, said direction switch being responsive to the manipulation of said dials, and means responsive to one operation of a said switching device for controlling said direction switch. 135
10. In a telephone system, telephone lines, an operator's trunk, a sending dial individually associated with each of said lines and with said trunk, groups of switching devices having permanently paired primary and secondary contacts for establishing interconnections between said lines and said trunk, a switching device of each group being required to complete a connection, a direction switch separate from said interconnections for controlling said devices, said direction switch being responsive to the manipulation of said dials, and means individual to said direction switch responsive to the actuation of a switching device of one of said groups under the control of said direction switch for transferring the control of said direction switch to another of said groups of switching devices. 140
11. In a telephone system, telephone lines, relays for establishing connections between said lines, a plurality of said relays being employed in establishing a connection, a direction switch separate from said established connection for controlling the operation of said relays, said direction switch being normally effective to cause the energization of one of said relays, and a relay associated with said direction switch responsive to the energization of said one of said relays for transferring the control of said switch to another of said relays. 145
12. In a telephone system, telephone lines, relays for establishing connections between

said lines, said relays being divided into groups and a relay of each group being employed in establishing a connection, a direction switch separate from said established connection for controlling the operation of said relays, said direction switch being normally effective to cause the energization of the relays of one of said groups, and a relay associated with said direction switch responsive to the energization of one of said relays of said one of said groups for transferring the control of said switch to another of said groups.

13. In a telephone system, a telephone line, a central office trunk, a relay under control of said line for placing a calling condition on said trunk, a source of current for energizing said relay, other means under control of said line for placing a calling condition on said trunk upon failure of said source of current, and a normally inoperative relay controlled in part by said means, said last relay being responsive to the extension of said central office trunk to remove said calling condition.

14. In a telephone system, a telephone line, a central office trunk, means at one end of said trunk for connecting said line thereto, means at the other end of said trunk for indicating a calling condition thereon and for extending said trunk, means associated with said line for placing a calling condition on said trunk, a relay for removing said calling condition responsive to the extension of said trunk, a source of current for energizing said relay, a normally inoperative relay independent of said source of current for removing said calling condition, and means for rendering said last relay operative upon failure of said source of current.

15. In a telephone system, telephone lines, link circuits, switching devices having permanently paired primary and secondary contacts for connecting said lines to said links, a mechanism normally effective to render said links selectable in the order of their sequence, a starting circuit for governing the control of said switching devices, said starting circuit including a relay ar-

rangement common to said link circuits arranged to measure time against the operation of said switching devices to change the order of selectability of said links and to transfer said starting circuit to another switching device upon the failure of one of said devices to connect a line to a link within a predetermined time.

16. In a telephone system, telephone lines, link circuits, switching devices having permanently paired primary and secondary contacts for connecting said lines to said links, a mechanism normally effective to render said links selectable in the order of their sequence, a starting circuit for controlling said switching devices, said starting circuit including a relay arrangement comprising a plurality of slow relays common to said link circuits arranged to measure time against the operation of said switching devices to change the order of selectability of said links and to transfer said starting circuit to another switching device upon the failure of one of said devices to connect a line to a link within a predetermined time.

17. In a telephone system, telephone lines, link circuits, switching devices having permanently paired primary and secondary contacts for connecting said lines to said links, a starting circuit arranged to normally cause the operation of a first-in-order switching device, said starting circuit having associated with it a relay arrangement for measuring time, said relay arrangement being arranged to transfer said starting circuit to a second-in-order switching device upon the failure of said first-in-order switching device to operate within a predetermined time, to thereafter transfer said starting circuit to a third-in-order switching device upon the failure of said second-in-order switching device to operate within a predetermined time, and to thereafter transfer said starting circuit in the manner aforesaid any desired number of times.

In witness whereof, I hereunto subscribe my name this 8th day of January A. D., 1921.

EDWARD E. HINRICHSEN.
